DISPLAY DEVICE AND METHOD OF DRIVING THE SAME

CROSS-REFERENCE TO RELATED APPLICATION

This U.S. non-provisional patent application claims priority under 35 U.S.C. § 119 of Korean Patent Application No. 10-2022-0072318, filed on Jun. 14, 2022, the entire contents of which are hereby incorporated by reference.

BACKGROUND

The present disclosure relates to a display device having improved display quality and a method of driving the same.

A light emitting display device displays an image using a light emitting diode that generates light by recombining electrons and holes. Such light emitting display devices have the advantage of a high response speed and a low power consumption. A light emitting display device includes pixels connected to data lines and scan lines. Each of the pixels includes a light emitting diode and a circuit for controlling an amount of a current flowing through the light emitting diode in response to a data signal. In this case, light having a predetermined luminance corresponding to the amount of the current flowing through the light emitting diode is generated.

SUMMARY

The present disclosure provides a display device having improved display quality by compensating for a threshold voltage of a driving transistor, and a method of driving the display device.

An embodiment of the inventive concept provides a display device including: a first circuit which is electrically connected to a data line, a plurality of scan lines, and a plurality of voltage lines, and includes a driving transistor including a first electrode, a second electrode, a gate electrode, and a back gate electrode; a light emitting element including an anode, and a cathode connected to the first circuit; and a second circuit including a first transistor connected between the back gate electrode of the driving transistor and a compensation voltage line, and a second transistor connected between the back gate electrode of the driving transistor and a first voltage line among the plurality of voltage lines.

In an embodiment, the first circuit may be provided in plurality, the light emitting element may be provided in plurality, the plurality of first circuits may be electrically connected, in one-to-one correspondence, to the plurality of light emitting elements, respectively, and the second circuit may be electrically connected to first circuits arranged in one row among the plurality of first circuits.

In an embodiment, the first circuit may be provided in plurality, the light emitting element may be provided in plurality, the second circuit may be provided in plurality, the plurality of first circuits may be electrically connected, in one-to-one correspondence, to the plurality of light emitting elements, respectively, and the plurality of second circuits may be electrically connected, in one-to-one correspondence, to the plurality of first circuits, respectively.

In an embodiment, the first circuit may include: a first pixel transistor connected between the first electrode of the driving transistor and the first voltage line; a second pixel transistor connected between the second electrode of the driving transistor and the cathode of the light emitting

element; a third pixel transistor connected between the cathode of the light emitting element and a second voltage line among the plurality of voltage lines; a fourth pixel transistor connected between the gate electrode of the driving transistor and a third voltage line among the plurality of voltage lines; a first capacitor connected between the gate electrode of the driving transistor and the first voltage line; a second capacitor including a first electrode connected to the gate electrode of the driving transistor and a second electrode; a fifth pixel transistor connected between the second electrode of the second capacitor and the data line; and a sixth pixel transistor connected between the second electrode of the second capacitor and a fourth voltage line among the plurality of voltage lines, wherein the anode of the light emitting element is connected to a fifth voltage line among the plurality of voltage lines.

In an embodiment, the first circuit may further include: a seventh pixel transistor connected between the gate electrode of the driving transistor and any one of the first electrode and the second electrode of the driving transistor; and an eighth pixel transistor connected between the other of the first electrode and the second electrode of the driving transistor and a sixth voltage line among the plurality of voltage lines.

In an embodiment, a gate electrode of the eighth pixel transistor and a gate electrode of the first transistor may be connected to the same scan line among the plurality of scan lines, and operations of the eighth pixel transistor and the first transistor may be controlled by the same scan signal.

In an embodiment, operations of the first pixel transistor and the second transistor may be controlled by a same signal.

In an embodiment, in an initialization period in which the third pixel transistor, the fourth pixel transistor, and the sixth pixel transistor are turned on, the first electrode of the second capacitor, the second electrode of the second capacitor, and the cathode of the light emitting element may be initialized.

In an embodiment, in a compensation period in which the first transistor, the seventh pixel transistor, and the eighth pixel transistor are turned on, a voltage obtained by adding a threshold voltage of the driving transistor to a voltage provided through the sixth voltage line may be applied to the gate electrode of the driving transistor.

In an embodiment, in a data write period in which the fifth pixel transistor is turned on, a data voltage provided through the data line may be applied to the second electrode of the second capacitor, and in an emission period in which the first pixel transistor and the second pixel transistor are turned on, a current path may be established between the first voltage line and the light emitting element, and a current, from which an influence of the threshold voltage of the driving transistor is removed, may flow through the current path.

In an embodiment, the third voltage line may be the fourth voltage line.

In an embodiment, the second voltage line may be the fifth voltage line.

In an embodiment, the driving transistor may be an N-type thin film transistor.

In an embodiment of the inventive concept, a display device includes: a first circuit including a driving transistor including a first electrode, a second electrode, a gate electrode, and a back gate electrode; and a light emitting element including an anode, and a cathode connected to the first circuit, wherein the first circuit is configured so that, in a compensation period, a first compensation voltage is applied to the back gate electrode of the driving transistor, a second

compensation voltage is applied to the first electrode of the driving transistor, and a voltage obtained by adding a threshold voltage of the driving transistor to the second compensation voltage is applied to the gate electrode of the driving transistor.

In an embodiment, the first circuit may be configured so that a current path is established between a driving voltage line and the light emitting element in an emission period, and a current, from which an influence of the threshold voltage of the driving transistor is removed, may flow through the current path in the emission period.

In an embodiment, the display device may further include: a first transistor connected between the back gate electrode of the driving transistor and a compensation voltage line to which the first compensation voltage is applied; and a second transistor connected between the back gate electrode of the driving transistor and a driving voltage line.

In an embodiment, the first circuit may be provided in plurality, the light emitting element may be provided in plurality, the plurality of first circuits may be electrically connected, in one-to-one correspondence, to the plurality of light emitting elements, respectively, and each of a first transistor and a second transistor may be electrically connected to first circuits arranged in one row among the plurality of first circuits.

In an embodiment, the first circuit may be provided in plurality, the light emitting element may be provided in plurality, the first transistor may be provided in plurality, the plurality of first circuits may be electrically connected, in one-to-one correspondence, to the plurality of light emitting elements, respectively, the plurality of first transistors may be electrically connected, in one-to-one correspondence, to the plurality of first circuits, respectively, and the plurality of second transistors may be electrically connected, in one-to-one correspondence, to the plurality of first circuits, respectively.

In an embodiment, the driving transistor may be an N-type thin film transistor.

In an embodiment of the inventive concept, a method of driving a display device, which includes a pixel including a first circuit including a driving transistor including a first electrode, a second electrode, a gate electrode, and a back gate electrode, and a light emitting element including an anode, and a cathode connected to the first circuit, includes: initializing the cathode of the light emitting element; compensating by applying a voltage obtained by adding a threshold voltage of the driving transistor to a second compensation voltage to the gate electrode of the driving transistor by applying a first compensation voltage to the back gate electrode of the driving transistor and applying the second compensation voltage to the first electrode of the driving transistor; and allowing the light emitting element to emit light by allowing a current, from which an influence of the threshold voltage of the driving transistor is removed, to flow from the first electrode of the driving transistor to the second electrode thereof.

BRIEF DESCRIPTION OF THE FIGURES

The accompanying drawings are included to provide a further understanding of the inventive concept, and are incorporated in and constitute a part of this specification. The drawings illustrate exemplary embodiments of the inventive concept and, together with the description, serve to describe principles of the inventive concept. In the drawings:

FIG. 1 is a block diagram of a display device according to an embodiment of the inventive concept;

FIG. 2 is an equivalent circuit diagram of a pixel according to an embodiment of the inventive concept;

5 FIG. 3 is a timing diagram for describing an operation of a pixel according to an embodiment of the inventive concept;

FIG. 4A is a view for describing an operation of a pixel in the first period illustrated in FIG. 3;

10 FIG. 4B is a view for describing an operation of a pixel in the second period illustrated in FIG. 3;

FIG. 4C is a view for describing an operation of a pixel in the third period illustrated in FIG. 3;

15 FIG. 4D is a view for describing an operation of a pixel in the fourth period illustrated in FIG. 3;

FIG. 5 is an equivalent circuit diagram of a pixel according to an embodiment of the inventive concept;

20 FIG. 6 is an equivalent circuit diagram of a pixel according to an embodiment of the inventive concept;

FIG. 7 is an equivalent circuit diagram of a pixel according to an embodiment of the inventive concept;

FIG. 8 is an equivalent circuit diagram of a pixel according to an embodiment of the inventive concept;

25 FIG. 9 is an equivalent circuit diagram of a pixel according to an embodiment of the inventive concept;

FIG. 10 is a block diagram of a display device according to an embodiment of the inventive concept; and

30 FIG. 11 is an equivalent circuit diagram of a row of pixels and a second circuit according to an embodiment of the inventive concept.

DETAILED DESCRIPTION

35 It will be understood that when an element or layer (or region, portion, and the like) is referred to as being "on", "connected to", or "coupled to" another element or layer, it can be directly on, connected to, or coupled to the other element or layer, or intervening elements or layers may be present.

40 Like reference numerals refer to like elements throughout this specification. In the figures, the ratios and dimensions (e.g., thicknesses) of elements are exaggerated for effective description of the technical contents.

45 As used herein, the word "or" means logical "or" so that, unless the context indicates otherwise, the expression "A, B, or C" means "A and B and C", "A and B but not C", "A and C but not B", "B and C but not A", "A but not B and not C", "B but not A and not C", and "C but not A and not B".

50 It will be understood that, although the terms first, second, etc. may be used herein to describe various elements, components, regions, layers, or sections, these elements, components, regions, layers, or sections should not be limited by these terms. These terms are only used to distinguish one element, component, region, layer, or section from another element, component, region, layer, or section. Thus, a first element, component, region, layer, or section discussed below could be termed a second element, component, region, layer, or section without departing from the teachings of the present invention.

55 As used herein, the singular forms, "a", "an", and "the" are intended to include the plural forms as well, unless the context clearly indicates otherwise. It will be understood that the singular forms, "a", "an", and "the" are intended to include the plural forms as well, unless the context clearly indicates otherwise.

60 Spatially relative terms, such as "beneath", "below", "lower", "above", and "upper", may be used herein for ease of description to describe one element or feature's relationship to another element(s) or feature(s) as illustrated in the figures. It will be understood that the spatially relative terms

are intended to encompass different orientations of the device in use or operation in addition to the orientation depicted in the figures.

It will be further understood that the terms "include," "comprise," and "have," and their variations such as "including" when used in this specification, specify the presence of stated features, integers, steps, operations, elements, components, or groups thereof, but do not preclude the presence or addition of one or more other features, integers, steps, operations, elements, components, or groups thereof.

Unless otherwise defined, all terms (including technical and scientific terms) used herein have the same meaning as commonly understood by one of ordinary skill in the art to which this invention belongs. It will be further understood that terms, such as those defined in commonly used dictionaries, should be interpreted as having meaning that is consistent with their meaning in the context of the relevant art and should not be interpreted in an overly idealized or overly formal sense unless expressly so defined herein.

Hereinafter, embodiments of the present inventive concept will be explained in detail with reference to the accompanying drawings.

FIG. 1 is a block diagram of a display device DD according to an embodiment of the inventive concept.

Referring to FIG. 1, the display device DD may include a display panel DP, a driving controller 100, and a panel driver. As an example of an embodiment of the inventive concept, the panel driver may include a data driving circuit 200 (or a data driver 200), a driving circuit 300, and a voltage generator 400.

The display panel DP may include a display area DA and a non-display area NDA. The display panel DP may include a plurality of pixels PX disposed in the display area DA. The display panel DP may further include first initialization scan lines GIL1 to GILn, second initialization scan lines GRL1 to GRLn, compensation scan lines GCL1 to GCLn, write scan lines GWL1 to GWLn, emission control lines EML1 to EMLn, and data lines DL1 to DLm. Here, n and m may be positive integers.

The display panel DP may be driven at a predetermined frequency, for example, about 60 Hz, about 120 Hz, or about 240 Hz. Alternatively, the display panel DP may be configured to operate in a first mode in which the display panel DP is driven at the predetermined frequency, or in a second mode in which the display panel DP is driven at a variable frame frequency. For example, the variable frame frequency may vary variously within a range of about 1 Hz to about 240 Hz, but is not particularly limited thereto.

The driving controller 100 receives an image signal RGB and a control signal CTRL. The driving controller 100 generates an image data signal DATA by converting the data format of the image signal RGB according to an interface specification between the driving controller 100 and the data driving circuit 200. The driving controller 100 outputs a first control signal SCS and a second control signal DCS.

The data driving circuit 200 receives the second control signal DCS and the image data signal DATA from the driving controller 100. The data driving circuit 200 converts the image data signal DATA into data signals and outputs the data signals to the data lines DL1 to DLm. The data signals are analog voltages corresponding to gradation values of the image data signal DATA. The data lines DL1 to DLm may be arranged in a first direction DR1 and may each extend in a second direction DR2 crossing the first direction DR1.

The driving circuit 300 may be disposed in the non-display area NDA of the display panel DP. However, the

driving circuit 300 is not particularly limited thereto. For example, at least a portion of the driving circuit 300 may be disposed in the display area DA. The driving circuit 300 may be provided in plurality. For example, the plurality of driving circuits 300 may be spaced apart from each other with the display area DA therebetween. However, this is only an example, and one of the two driving circuits 300 illustrated in FIG. 1 may be omitted.

Each of the plurality of pixels PX according to an embodiment of the inventive concept includes a light emitting element ED (see FIG. 2), a first circuit PXC (see FIG. 2) for controlling light emission of the light emitting element ED, and a second circuit CPC (see FIG. 2) electrically connected to the first circuit PXC. The first circuit PXC and the second circuit CPC may constitute one pixel circuit.

The first circuit PXC may include one or more transistors and one or more capacitors. The driving circuits 300 may include transistors provided through a process the same as that of the first circuit PXC and the second circuit CPC.

Each of the first initialization scan lines GIL1 to GILn, the second initialization scan lines GRL1 to GRLn, the compensation scan lines GCL1 to GCLn, the write scan lines GWL1 to GWLn, and the emission control lines EML1 to EMLn may be electrically connected to the driving circuits 300 to receive a signal from each of the driving circuits 300. For example, each of one first initialization scan line GILL one second initialization scan line GRL1, one compensation scan line GCL1, one write scan line GWL1, and one emission control line EML1 may receive a same signal from the two driving circuits 300.

The first initialization scan lines GIL1 to GILn, the second initialization scan lines GRL1 to GRLn, the compensation scan lines GCL1 to GCLn, the write scan lines GWL1 to GWLn, and the emission control lines EML1 to EMLn may each extend in the first direction DR1 and may be spaced apart from each other in the second direction DR2.

Each of the plurality of pixels PX may be electrically connected to four scan lines, one emission control line, and one data line. For example, as illustrated in FIG. 1, pixels PX in a first row may be connected to the scan lines GILL GCL1, GWL1, and GRL1, and the emission control line EML1. Pixels PX in a first column may be connected to the data line DL1. In addition, pixels PX in a j-th row may be connected to the scan lines GILj, GCLj, GWLj, and GRLj, and the emission control line EMLj. Here, j may be a positive integer less than or equal to n.

The voltage generator 400 generates voltages necessary for the operation of the display panel DP. In this embodiment, the voltage generator 400 may generate a first driving voltage ELVSS, a second driving voltage ELVDD, an initialization voltage VCINT, a second compensation voltage VCOMP, a reference voltage VREF, and a first compensation voltage VBML.

FIG. 2 is an equivalent circuit diagram of a pixel PXij according to an embodiment of the inventive concept.

Referring to FIGS. 1 and 2, a pixel PXij may include the first circuit PXC, the second circuit CPC, and at least one light emitting element ED. The pixel PXij may be connected to a j-th first initialization scan line GILj, a j-th second initialization scan line GRLj, a j-th compensation scan line GCLj, a j-th write scan line GWLj, a j-th emission control line EMLj, and an i-th data line DLi.

Each of the plurality of pixels PX illustrated in FIG. 1 may have the same circuit configuration as the pixel PXij illustrated in FIG. 2. Accordingly, in the display panel DP, each of the first circuit PXC, the light emitting element ED, and the second circuit CPC may be provided in plurality. The

plurality of first circuits PXC may be electrically connected, in one-to-one correspondence, to the plurality of light emitting elements ED, respectively. In addition, the plurality of second circuits CPC may be electrically connected, in one-to-one correspondence, to the plurality of first circuits PXC, respectively. In this case, the number of the first circuits PXC included in the display panel DP may be the same as the number of the second circuits CPC included therein.

Referring to FIG. 2, the first circuit PXC may include a driving transistor DTR, first to eighth pixel transistors T₁, T₂, T₃, T₄, T₅, T₆, T₇, and T₈, a first capacitor C₁, and a second capacitor C₂. The second circuit CPC may include a first transistor CT₁ and a second transistor CT₂.

Each of the driving transistor DTR, the first to eighth pixel transistors T₁, T₂, T₃, T₄, T₅, T₆, T₇, and T₈, the first transistor CT₁, and the second transistor CT₂ may be an N-type thin film transistor having an oxide semiconductor as a semiconductor layer. In particular, in the case that the N-type thin film transistor is applied to the driving transistor DTR, the variation of element properties due to previous data may be reduced compared with the case that a P-type thin film transistor is applied. Accordingly, the property of overcoming an instantaneous afterimage may be improved. The N-type thin film transistor may be an N-channel metal-oxide semiconductor thin film transistor including an oxide semiconductor layer. The P-type thin film transistor may be a P-channel metal-oxide semiconductor thin film transistor including a silicon semiconductor layer.

The light emitting element ED may include an anode AE and a cathode CE. In the case that the light emitting element ED is an organic light emitting element, the light emitting element ED may further include an organic layer disposed between the anode AE and the cathode CE. The cathode CE of the light emitting element ED may be connected to the first circuit PXC. That is, the light emitting element ED may be an inverted organic light emitting diode (OLED). The light emitting element ED may emit light corresponding to an amount of a current flowing through the driving transistor DTR of the first circuit PXC.

According to an embodiment of the inventive concept, the driving transistor DTR may be an N-type thin film transistor, and the cathode CE of the light emitting element ED may be connected to a drain (or a second electrode TE₂) of the driving transistor DTR. In this case, even when the light emitting element ED deteriorates, the voltage of the terminal of a source (or a first electrode TE₁) of the driving transistor DTR may not shift. That is, even when the light emitting element ED deteriorates, a gate-source voltage of the driving transistor DTR may not change. Accordingly, even when the usage time of the display panel DP increases, the variation in the amount of the current flowing through the driving transistor DTR is reduced, so that an afterimage defect (or a long-term afterimage defect) of the display panel DP may be reduced, and the lifespan of the display panel DP may be improved.

The j-th first initialization scan line GIL_j may transmit a first initialization scan signal GI_j, the j-th second initialization scan line GRL_j may transmit a second initialization scan signal GR_j, the j-th compensation scan line GCL_j may transmit a compensation scan signal GC_j, the j-th write scan line GWL_j may transmit a write scan signal GW_j, the j-th emission control line EML_j may transmit an emission control signal EM_j, and the i-th data line DLI may transmit a data signal Di. The data signal Di may have a voltage level corresponding to a gradation value of the image data signal DATA outputted from the driving controller 100.

In addition, the pixel PX_{ij} may be connected to first to sixth voltage lines VL₁, VL₂, VL₃, VL₄, VL₅, and VL₆, and a compensation voltage line VCL. The first voltage line VL₁ may transmit the first driving voltage ELVSS and may be referred to as a driving voltage line. The second voltage line VL₂ may transmit the initialization voltage VCINT. The third voltage line VL₃ and the fourth voltage line VL₄ may transmit the reference voltage VREF. The third voltage line VL₃ may be the fourth voltage line VL₄. Accordingly, the fourth pixel transistor T₄ and the sixth pixel transistor T₆ may be connected to the same voltage line (the third voltage line VL₃ or the fourth voltage line VL₄). The fifth voltage line VL₅ may transmit the second driving voltage ELVDD. The sixth voltage line VL₆ may transmit the second compensation voltage VCOMP. The compensation voltage line VCL may transmit the first compensation voltage VBML.

The driving transistor DTR may include the first electrode TE₁, the second electrode TE₂, a gate electrode TG, and a back gate electrode TBG. The gate electrode TG may be connected to a first node N₁, and the first electrode TE₁ may be connected to a second node N₂. The first electrode TE₁ may be referred to as the source of the driving transistor DTR, and the second electrode TE₂ may be referred to as the drain of the driving transistor DTR.

The first capacitor C₁ and the second capacitor C₂ may be connected to the first node N₁. The first capacitor C₁ may be connected between the first node N₁ and the first voltage line VL₁. The second capacitor C₂ may include a first electrode CE₁ and a second electrode CE₂, the first electrode CE₁ may be connected to the first node N₁, and the second electrode CE₂ may be connected to a third node N₃.

The first pixel transistor T₁ may be connected between the first electrode TE₁ of the driving transistor DTR and the first voltage line VL₁. The second pixel transistor T₂ may be connected between the second electrode TE₂ of the driving transistor DTR and the cathode CE of the light emitting element ED. Operations of the first pixel transistor T₁ and the second pixel transistor T₂ may be controlled in response to the emission control signal EM_j provided through the j-th emission control line EML_j. As the first pixel transistor T₁ and the second pixel transistor T₂ are turned on, a current path may be established between the first voltage line VL₁ and the light emitting element ED through the first pixel transistor T₁, the second pixel transistor T₂, and the driving transistor DTR.

The third pixel transistor T₃ may be connected between the cathode CE of the light emitting element ED and the second voltage line VL₂. An operation of the third pixel transistor T₃ may be controlled in response to the second initialization scan signal GR_j provided through the j-th second initialization scan line GRL_j. The third pixel transistor T₃ may be turned on according to the second initialization scan signal GR_j to electrically connect the cathode CE of the light emitting element ED and the second voltage line VL₂.

The fourth pixel transistor T₄ may be connected between the gate electrode TG of the driving transistor DTR and the third voltage line VL₃. An operation of the fourth pixel transistor T₄ may be controlled in response to the first initialization scan signal GI_j provided through the j-th first initialization scan line GIL_j. The fourth pixel transistor T₄ may be turned on according to the first initialization scan signal GI_j to electrically connect the gate electrode TG of the driving transistor DTR and the third voltage line VL₃.

The fifth pixel transistor T₅ may be connected between the second electrode CE₂ of the second capacitor C₂ and the i-th data line DLI. An operation of the fifth pixel transistor

T₅ may be controlled in response to the write scan signal GW_j provided through the j-th write scan line GWL_j. The fifth pixel transistor T₅ may be turned on according to the write scan signal GW_j to transmit, to the third node N₃, the data signal Di transmitted from the i-th data line DL_i. The fifth pixel transistor T₅ may be referred to as a switching thin film transistor.

The sixth pixel transistor T₆ may be connected between the second electrode CE₂ of the second capacitor C₂ and the fourth voltage line VL₄. An operation of the sixth pixel transistor T₆ may be controlled in response to the second initialization scan signal GR_j provided through the j-th second initialization scan line GRL_j. The sixth pixel transistor T₆ may be turned on according to the second initialization scan signal GR_j to electrically connect the third node N₃ and the fourth voltage line VL₄.

The seventh pixel transistor T₇ may be connected between the gate electrode TG of the driving transistor DTR and the second electrode TE₂ of the driving transistor DTR. The eighth pixel transistor T₈ may be connected between the first electrode TE₁ of the driving transistor DTR and the sixth voltage line VL₆. Operations of the seventh pixel transistor T₇ and the eighth pixel transistor T₈ may be controlled in response to the compensation scan signal GC_j provided through the j-th compensation scan line GCL_j.

The anode AE of the light emitting element ED may be connected to the fifth voltage line VL₅. The second driving voltage ELVDD may be provided to the fifth voltage line VL₅. The second driving voltage ELVDD may have a voltage level higher than that of the first driving voltage ELVSS.

The second circuit CPC may include the first transistor CT₁ and the second transistor CT₂.

The first transistor CT₁ may be connected between the back gate electrode TBG of the driving transistor DTR and the compensation voltage line VCL. Gate electrodes of the first transistor CT₁ and the eighth pixel transistor T₈ may be connected to the same scan line, for example, the j-th compensation scan line GCL_j. Accordingly, an operation of the first transistor CT₁ may be controlled in response to the compensation scan signal GC_j provided through the j-th compensation scan line GCL_j.

The second transistor CT₂ may be connected between the back gate electrode TBG of the driving transistor DTR and the first voltage line VL₁. Gate electrodes of the second transistor CT₂ and the first pixel transistor T₁ may be connected to the same line, for example, the j-th emission control line EML_j. Accordingly, an operation of the second transistor CT₂ may be controlled in response to the emission control signal EM_j provided through the j-th emission control line EML_j. For example, in a period in which the emission control signal EM_j is activated, that is, in a fourth period SC₄ (see FIG. 3), the back gate electrode TBG of the driving transistor DTR may be synchronized with the second node N₂ by the second transistor CT₂.

FIG. 3 is a timing diagram for describing an operation of a pixel PX_{ij} according to an embodiment of the inventive concept.

Referring to FIGS. 2 and 3, waveforms of the emission control signal EM_j, the first initialization scan signal GI_j, the compensation scan signal GC_j, the second initialization scan signal GR_j, the write scan signal GW_j, and voltages VN₁, VN₂, and VN₃ of the first to third nodes N₁, N₂, and N₃ are illustrated.

The pixel PX_{ij} may be driven while passing through a first period SC₁, a second period SC₂, a third period SC₃, and the fourth period SC₄. The first period SC₁, the second period

SC₂, the third period SC₃, and the fourth period SC₄ are periods divided according to the operation of the pixel PX_{ij}, and the first period SC₁ may be referred to as an initialization period, the second period SC₂ may be referred to as a compensation period, the third period SC₃ may be referred to as a data write period, and the fourth period SC₄ may be referred to as an emission period.

FIG. 4A is a view for describing an operation of a pixel PX_{ij} in the first period SC₁ illustrated in FIG. 3.

Referring to FIGS. 3 and 4A, the first period SC₁ is a period in which both ends of the second capacitor C₂ and the cathode CE of the light emitting element ED are initialized. In the first period SC₁, the first initialization scan signal GI_j and the second initialization scan signal GR_j may each have an active level (e.g., a high level).

When the third pixel transistor T₃ is turned on, the cathode CE of the light emitting element ED may be initialized to the initialization voltage VCINT. The first electrode CE₁ of the second capacitor C₂ or the first node N₁ may be initialized to the reference voltage VREF when the fourth pixel transistor T₄ is turned on, and the second electrode CE₂ of the second capacitor C₂ or the third node N₃ may be initialized to the reference voltage VREF when the sixth pixel transistor T₆ is turned on.

FIG. 4B is a view for describing an operation of a pixel PX_{ij} in the second period SC₂ illustrated in FIG. 3.

Referring to FIGS. 3 and 4B, the second period SC₂ is the compensation period in which a threshold voltage of the driving transistor DTR is compensated for. In the second period SC₂, the second initialization scan signal GR_j and the compensation scan signal GC_j may each have the active level (e.g., the high level).

When the first transistor CT₁ is turned on, the first compensation voltage VBML may be applied to the back gate electrode TBG of the driving transistor DTR. When the eighth pixel transistor T₈ is turned on, the second compensation voltage VCOMP may be applied to the first electrode TE₁ (or the source) of the driving transistor DTR, and a voltage VN₂ of the second node N₂ may be the second compensation voltage VCOMP.

A reverse bias voltage (hereinafter referred to as V_{BS}) between the back gate electrode TBG and the terminal of the source of the driving transistor DTR may be kept constant as a difference between the first compensation voltage VBML and the second compensation voltage VCOMP. That is, the constant V_{BS} is applied in the compensation period regardless of a previously written data voltage. Accordingly, the threshold voltage of the driving transistor DTR may shift in a constant way without being affected by the data voltage.

According to an embodiment of the inventive concept, the threshold voltage of the driving transistor DTR may be shifted in a positive direction by adjusting the voltage level of the first compensation voltage VBML. In this case, the threshold voltage of the driving transistor DTR, which is an N-type thin film transistor, may be compensated for in a diode connection method.

When the seventh pixel transistor T₇ is turned on, the second electrode TE₂ (or the drain) of the driving transistor DTR may be connected to the gate electrode TG of the driving transistor DTR. That is, the driving transistor DTR may be diode-connected. In this case, a voltage VN₁ of the first node N₁ may be changed to the sum of the second compensation voltage VCOMP and the threshold voltage (hereinafter referred to as V_{TH}) of the driving transistor DTR. Compensation stability may be improved because a value reflecting the threshold voltage of the driving transistor DTR is directly applied to the first node N₁.

11

FIG. 4C is a view for describing an operation of a pixel PXij in the third period SC3 illustrated in FIG. 3.

Referring to FIGS. 3 and 4C, the third period SC3 is the data write period in which the data signal Di is inputted. In the third period SC3, the write scan signal GWj may have the active level (e.g., the high level). The fifth pixel transistor T5 may be turned on in response to the write scan signal GWj.

When the fifth pixel transistor T5 is turned on, a voltage of the second electrode CE2 of the second capacitor C2, i.e., a voltage VN3 of the third node N3, may be changed from the reference voltage VREF to a data voltage (hereinafter referred to as V_{DATA}) corresponding to the data signal Di. Accordingly, a voltage of the first electrode CE1 of the second capacitor C2, i.e., the voltage VN1 of the first node N1, may be changed to a value of the following expression.

$$(V_{DATA} - VREF) \frac{C1_C}{C1_C + C2_C} + (VCOMP + V_{TH})$$

V_{DATA} is the data voltage corresponding to the data signal Di, VREF is the reference voltage VREF, $C1_C$ is capacitance of the first capacitor C1, $C2_C$ is capacitance of the second capacitor C2, VCOMP is the second compensation voltage VCOMP, and V_{TH} is the threshold voltage of the driving transistor DTR.

FIG. 4D is a view for describing an operation of a pixel PXij in the fourth period SC4 illustrated in FIG. 3.

Referring to FIGS. 3 and 4D, the fourth period SC4 is the emission period in which the light emitting element ED emits light. In the fourth period SC4, the emission control signal EMj may have the active level (e.g., the high level). The first and second pixel transistors T1 and T2 may be turned on in response to the emission control signal EMj.

When the first and second pixel transistors T1 and T2 are turned on, a current path is established between the first voltage line VL1 and the light emitting element ED. As indicated in the following equation, a current (I_{DS}), from which the influence of the threshold voltage of the driving transistor DTR is removed, may flow through the current path. According to an embodiment of the inventive concept, as the first compensation voltage VBML is applied to the gate electrode TG of the driving transistor DTR, i.e., to the first node N1, compensation stability may be improved.

$$\begin{aligned} I_{DS} &= K \times (VN1 - VN2 - V_{TH})^2 \\ &= K \times \left((V_{DATA} - VREF) \frac{C1_C}{C1_C + C2_C} + (VCOMP + V_{TH}) - VN2 - V_{TH} \right)^2 \\ &= K \times \left((V_{DATA} - VREF) \frac{C1_C}{C1_C + C2_C} + VCOMP + VN2 \right)^2 \end{aligned}$$

K is μ -Cox-W/L, wherein μ may be electric field mobility, Cox may be the capacitance of a gate insulating film, and W/L is the ratio of width to length of a channel of the driving transistor DTR.

FIG. 5 is an equivalent circuit diagram of a pixel PXij-1 according to an embodiment of the inventive concept. When a description is given with reference to FIG. 5, portions different from those of FIG. 2 will be described, and the same components are denoted by the same reference numerals, and a description of the same components will not be given.

12

Referring to FIG. 5, a pixel PXij-1 may include a first circuit PXC-1, a second circuit CPC, and at least one light emitting element ED. The first circuit PXC-1 may include a driving transistor DTR, first to eighth pixel transistors T1, T2, T3, T4, T5, T6, T7-1, and T8-1, a first capacitor C1, and a second capacitor C2. The second circuit CPC may include a first transistor CT1 and a second transistor CT2.

The seventh pixel transistor T7-1 may be connected between a gate electrode TG of the driving transistor DTR and a first electrode TE1 of the driving transistor DTR. The eighth pixel transistor T8-1 may be connected between a second electrode TE2 of the driving transistor DTR and a sixth voltage line VL6. Operations of the seventh pixel transistor T7-1 and the eighth pixel transistor T8-1 may be controlled in response to a compensation scan signal GCj provided through a j-th compensation scan line GCLj.

When the seventh pixel transistor T7-1 is turned on, the first electrode TE1 of the driving transistor DTR may be connected to the gate electrode TG of the driving transistor DTR. When the eighth pixel transistor T8-1 is turned on, a second compensation voltage VCOMP may be applied to the second electrode TE2 of the driving transistor DTR.

FIG. 6 is an equivalent circuit diagram of a pixel PXij-2 according to an embodiment of the inventive concept. When a description is given with reference to FIG. 6, portions different from those of FIG. 2 will be described, and the same components are denoted by the same reference numerals, and a description of the same components will not be given.

Referring to FIG. 6, a pixel PXij-2 may include a first circuit PXC-2, a second circuit CPC, and at least one light emitting element ED.

The pixel PXij-2 may be connected to first to sixth voltage lines VL1, VL2, VL3-1, VL4-1, VL5, and VL6, and a compensation voltage line VCL. The third voltage line VL3-1 may transmit a first reference voltage VREF1, and the fourth voltage line VL4-1 may transmit a second reference voltage VREF2. The first reference voltage VREF1 and the second reference voltage VREF2 may have the same voltage levels or different voltage levels.

FIG. 7 is an equivalent circuit diagram of a pixel PXij-3 according to an embodiment of the inventive concept. When a description is given with reference to FIG. 7, portions different from those of FIG. 2 will be described, and the same components are denoted by the same reference numerals, and a description of the same components will not be given.

Referring to FIG. 7, a pixel PXij-3 may include a first circuit PXC-3, a second circuit CPC, and at least one light emitting element ED.

The pixel PXij-3 may be connected to first to sixth voltage lines VL1, VL2-1, VL3, VL4, VL5, and VL6, and a compensation voltage line VCL. The second voltage line VL2-1 may transmit a second driving voltage ELVDD. The fifth voltage line VL5 may transmit the second driving voltage ELVDD. The second voltage line VL2-1 may be the fifth voltage line VL5. That is, a third pixel transistor T3 and an anode AE of the light emitting element ED may be connected to the same voltage line (the second voltage line VL2-1 or the fifth voltage line VL5).

FIG. 8 is an equivalent circuit diagram of a pixel PXij-4 according to an embodiment of the inventive concept. When a description is given with reference to FIG. 8, portions different from those of FIG. 2 will be described, and the same components are denoted by the same reference numerals, and a description of the same components will not be given.

Referring to FIG. 8, a pixel PX_{ij-4} may include a first circuit $PXC-4$, a second circuit CPC , and at least one light emitting element ED . The pixel PX_{ij-4} may be connected to a j -th first initialization scan line GIL_j , a j -th second initialization scan line $GRL1_j$, a j -th third initialization scan line $GRL2_j$, a j -th first compensation scan line $GCL1_j$, a j -th second compensation scan line $GCL2_j$, a j -th write scan line GWL_j , a j -th first emission control line $EML1_j$, a j -th second emission control line $EML2_j$, and an i -th data line DL_i .

The j -th first initialization scan line GIL_j may transmit a first initialization scan signal GI_j , the j -th second initialization scan line $GRL1_j$ may transmit a second initialization scan signal $GR1_j$, and the j -th third initialization scan line $GRL2_j$ may transmit a third initialization scan signal $GR2_j$. The second initialization scan signal $GR1_j$ and the third initialization scan signal $GR2_j$ may have the same waveforms, but are not particularly limited thereto, and may have different waveforms.

The j -th first compensation scan line $GCL1_j$ may transmit a first compensation scan signal $GC1_j$, and the j -th second compensation scan line $GCL2_j$ may transmit a second compensation scan signal $GC2_j$. The first compensation scan signal $GC1_j$ and the second compensation scan signal $GC2_j$ may have the same waveforms, but are not particularly limited thereto, and may have different waveforms.

The j -th first emission control line $EML1_j$ may transmit a first emission control signal $EM1_j$, and the j -th second emission control line $EML2_j$ may transmit a second emission control signal $EM2_j$. The first emission control signal $EM1_j$ and the second emission control signal $EM2_j$ may have the same waveforms, but are not particularly limited thereto, and may have different waveforms.

The j -th write scan line GWL_j may transmit a write scan signal GW_j , and the i -th data line DL_i may transmit a data signal Di . The data signal Di may have a voltage level corresponding to a gradation value of an image data signal $DATA$ outputted from a driving controller 100 .

FIG. 9 is an equivalent circuit diagram of a pixel PX_{ij-5} according to an embodiment of the inventive concept. When a description is given with reference to FIG. 9, portions different from those of FIG. 2 will be described, and the same components are denoted by the same reference numerals, and a description of the same components will not be given.

Referring to FIG. 9, a pixel PX_{ij-5} may include a first circuit $PXC-5$, a second circuit CPC , and at least one light emitting element ED . The pixel PX_{ij-5} may be connected to a j -th first initialization scan line $GWL(j-x)$, a j -th second initialization scan line GRL_j , a j -th compensation scan line GCL_j , a j -th write scan line GWL_j , a j -th emission control line EML_j , and an i -th data line DL_i .

The j -th first initialization scan line $GWL(j-x)$ may correspond to a write scan line of another row, for example, a $(j-x)$ -th write scan line $GWL(j-x)$. Here, x may be a positive integer or a negative integer. According to the embodiment illustrated in FIG. 9, the write scan line $GWL(j-x)$ of the other row and a write scan signal $GW(j-x)$ provided thereto may be used as the first initialization scan line and a first initialization scan signal thereof, respectively.

FIG. 10 is a block diagram of a display device $DD-1$ according to an embodiment of the inventive concept. FIG. 11 is an equivalent circuit diagram of a row of pixels PX_{aj1} to PX_{ajm} and a second circuit CPC_{aj} according to an embodiment of the inventive concept. When descriptions are given with reference to FIGS. 10 and 11, portions different from those of FIGS. 1 and 2 will be described, and the same

components are denoted by the same reference numerals, and a description of the same components will not be given.

Referring to FIGS. 10 and 11, a display device $DD-1$ may include a display panel $DP-1$, a driving controller 100 , a panel driver, and second circuits $CPCa1$ to $CPCan$. As an example of an embodiment of the inventive concept, the panel driver may include a data driving circuit 200 (or a data driver 200), driving circuits 300 , and a voltage generator 400 . The display panel $DP-1$ may include a display area DA and a non-display area NDA . The display panel $DP-1$ may include a plurality of pixels PXa disposed in the display area DA .

Each of the plurality of pixels PXa according to an embodiment of the inventive concept may include a light emitting element ED and a first circuit $PXCa$ for controlling light emission of the light emitting element ED .

The light emitting element ED may be provided in plurality. For example, the number of the light emitting elements ED provided may be $m \times n$. The first circuit $PXCa$ may be provided in plurality. For example, the number of the first circuits $PXCa$ provided may be $m \times n$. The plurality of first circuits $PXCa$ may be electrically connected, in one-to-one correspondence, to the plurality of light emitting elements ED , respectively.

Each of the second circuits $CPCa1$ to $CPCan$ may be electrically connected to first circuits $PXCa$ arranged in one row among the plurality of first circuits $PXCa$. Pixels PX_{aj1} to PX_{ajm} arranged in a j -th row are illustrated as an example in FIG. 11. A first pixel PX_{aj1} among the pixels PX_{aj1} to PX_{ajm} arranged in the j -th row may be connected to a first data line DL_1 to receive a data signal $D1$, and an m -th pixel PX_{ajm} among the pixels PX_{aj1} to PX_{ajm} arranged in the j -th row may be connected to an m -th data line DL_m to receive a data signal Dm . The m number of pixels PX_{aj1} to PX_{ajm} arranged in one row may be electrically connected to one second circuit CPC_{aj} . Accordingly, the number of the first circuits $PXCa$ included in the display panel $DP-1$ may be greater than the number of the second circuits $CPCa1$ to $CPCan$ included therein.

Although, in an embodiment of the inventive concept, the plurality of first circuits $PXCa$ may be disposed in the display area DA , and the second circuits $CPCa1$ to $CPCan$ may be disposed in the non-display area NDA , an embodiment of the inventive concept is not particularly limited thereto. For example, the second circuits $CPCa1$ to $CPCan$ may be disposed in the display area DA , or alternatively, a portion of each of the second circuits $CPCa1$ to $CPCan$ may be disposed in the display area DA , and another portion of each of the second circuits $CPCa1$ to $CPCan$ may be disposed in the non-display area NDA . Alternatively, some of the second circuits $CPCa1$ to $CPCan$ may be disposed in the display area DA , and the others of the second circuits $CPCa1$ to $CPCan$ may be disposed in the non-display area NDA .

In an embodiment of the inventive concept, some of first to eighth pixel transistors $T1, T2, T3, T4, T5, T6, T7$, and $T8$ included in each of the plurality of first circuits $PXCa$ may be disposed in the non-display area NDA . In addition, at least one pixel transistor disposed in the non-display area NDA among the first to eighth pixel transistors $T1$ to $T8$ may be connected in common to the plurality of pixels PXa . For example, at least one pixel transistor may be connected in common to pixels PXa arranged in the same row, e.g., the pixels PX_{aj1} to PX_{ajm} arranged in the j -th row.

In the embodiments illustrated in FIGS. 10 and 11, the first circuit $PXCa$ may be referred to as a pixel circuit $PXCa$. Because each of the second circuits $CPCa1$ to $CPCan$ is

15

connected to the plurality of first circuits PXCa, the second circuits CPCa1 to CPCa5 may be referred to as common circuits CPCa1 to CPCa5.

Although, in FIGS. 10 and 11, one second circuit is illustrated as an example to be connected to a row of pixels PXa, an embodiment of the inventive concept is not particularly limited thereto. For example, a second circuit connected to some of a row of pixels PXa and another second circuit connected to the rest of the row of pixels PXa may be provided.

As described above, the driving transistor may be an N-type thin film transistor, and the cathode of the light emitting element may be connected to the drain of the driving transistor. In this case, even when the light emitting element deteriorates, the voltage of the terminal of the source of the driving transistor may not shift. That is, even when the usage time of the display panel increases, the variation in the amount of the current flowing through the driving transistor is reduced, so that an afterimage defect (or a long-term afterimage defect) of the display panel may be reduced, and the lifespan of the display panel may be improved.

In addition, the threshold voltage of the driving transistor may be compensated for by the second circuit. The reverse bias voltage between the back gate electrode and the terminal of the source of the driving transistor may be kept constant as a difference between the first compensation voltage and the second compensation voltage. By adjusting the voltage level of the first compensation voltage, the threshold voltage of the driving transistor may be shifted in a positive direction. In this case, the threshold voltage of the driving transistor, which is the N-type thin film transistor, may be compensated for in a diode connection method. In this case, compensation stability may be improved because a value reflecting the threshold voltage of the driving transistor is directly applied to the gate electrode of the driving transistor.

Although embodiments of the present inventive concepts have been described, various modifications and similar arrangements of such embodiments will be apparent to a person of ordinary skill in the art. Accordingly, the inventive concepts are not limited to such embodiments, but rather to the scope and spirit of the appended claims.

What is claimed is:

1. A display device comprising:
a first circuit which is electrically connected to a data line, a plurality of scan lines, and a plurality of voltage lines, and includes a driving transistor including a first electrode, a second electrode, a gate electrode, and a back gate electrode;
a light emitting element including an anode, and a cathode connected to the first circuit; and
a second circuit including a first transistor connected between the back gate electrode of the driving transistor and a compensation voltage line, and a second transistor connected between the back gate electrode of the driving transistor and a first voltage line among the plurality of voltage lines.
2. The display device of claim 1, wherein the first circuit is provided in plurality, the light emitting element is provided in plurality, the plurality of first circuits are electrically connected, in one-to-one correspondence, to the plurality of light emitting elements, respectively, and the second circuit is electrically connected to first circuits arranged in one row among the plurality of first circuits.
3. The display device of claim 1, wherein the first circuit is provided in plurality, the light emitting element is pro-

16

vided in plurality, the second circuit is provided in plurality, the plurality of first circuits are electrically connected, in one-to-one correspondence, to the plurality of light emitting elements, respectively, and the plurality of second circuits are electrically connected, in one-to-one correspondence, to the plurality of first circuits, respectively.

4. The display device of claim 1, wherein the first circuit comprises:

- a first pixel transistor connected between the first electrode of the driving transistor and the first voltage line;
- a second pixel transistor connected between the second electrode of the driving transistor and the cathode of the light emitting element;
- a third pixel transistor connected between the cathode of the light emitting element and a second voltage line among the plurality of voltage lines;
- a fourth pixel transistor connected between the gate electrode of the driving transistor and a third voltage line among the plurality of voltage lines;
- a first capacitor connected between the gate electrode of the driving transistor and the first voltage line;
- a second capacitor including a first electrode connected to the gate electrode of the driving transistor and a second electrode;
- a fifth pixel transistor connected between the second electrode of the second capacitor and the data line; and
- a sixth pixel transistor connected between the second electrode of the second capacitor and a fourth voltage line among the plurality of voltage lines,

wherein the anode of the light emitting element is connected to a fifth voltage line among the plurality of voltage lines.

5. The display device of claim 4, wherein the first circuit further comprises:

- a seventh pixel transistor connected between the gate electrode of the driving transistor and any one of the first electrode and the second electrode of the driving transistor; and
- an eighth pixel transistor connected between the other of the first electrode and the second electrode of the driving transistor and a sixth voltage line among the plurality of voltage lines.

6. The display device of claim 5, wherein a gate electrode of the eighth pixel transistor and a gate electrode of the first transistor are connected to the same scan line among the plurality of scan lines, and operations of the eighth pixel transistor and the first transistor are controlled by the same scan signal.

7. The display device of claim 5, wherein operations of the first pixel transistor and the second transistor are controlled by a same signal.

8. The display device of claim 5, wherein, in an initialization period in which the third pixel transistor, the fourth pixel transistor, and the sixth pixel transistor are turned on, the first electrode of the second capacitor, the second electrode of the second capacitor, and the cathode of the light emitting element are initialized.

9. The display device of claim 5, wherein, in a compensation period in which the first transistor, the seventh pixel transistor, and the eighth pixel transistor are turned on, a voltage obtained by adding a threshold voltage of the driving transistor to a voltage provided through the sixth voltage line is applied to the gate electrode of the driving transistor.

10. The display device of claim 9, wherein, in a data write period in which the fifth pixel transistor is turned on, a data voltage provided through the data line is applied to the second electrode of the second capacitor, and

in an emission period in which the first pixel transistor and the second pixel transistor are turned on, a current path is established between the first voltage line and the light emitting element, and a current, from which an influence of the threshold voltage of the driving transistor is removed, flows through the current path.

11. The display device of claim 5, wherein the third voltage line is the fourth voltage line.

12. The display device of claim 5, wherein the second voltage line is the fifth voltage line.

13. The display device of claim 1, wherein the driving transistor is an N-type thin film transistor.

14. A display device comprising:

a first circuit including a driving transistor including a first electrode, a second electrode, a gate electrode, and a back gate electrode; and

a light emitting element including an anode, and a cathode connected to the first circuit,

wherein the first circuit is configured so that, in a compensation period, a first compensation voltage is applied to the back gate electrode of the driving transistor, a second compensation voltage is applied to the first electrode of the driving transistor, and a voltage obtained by adding a threshold voltage of the driving transistor to the second compensation voltage is applied to the gate electrode of the driving transistor.

15. The display device of claim 14, wherein the first circuit is configured so that a current path is established between a driving voltage line and the light emitting element in an emission period, and a current, from which an influence of the threshold voltage of the driving transistor is removed, flows through the current path in the emission period.

16. The display device of claim 14, further comprising: a first transistor connected between the back gate electrode of the driving transistor and a compensation voltage line to which the first compensation voltage is applied; and

a second transistor connected between the back gate electrode of the driving transistor and a driving voltage line.

17. The display device of claim 16, wherein the first circuit is provided in plurality, the light emitting element is provided in plurality, the plurality of first circuits are electrically connected, in one-to-one correspondence, to the plurality of light emitting elements, respectively, and each of the first transistor and the second transistor is electrically connected to first circuits arranged in one row among the plurality of first circuits.

18. The display device of claim 16, wherein the first circuit is provided in plurality, the light emitting element is provided in plurality, the first transistor is provided in plurality, the second transistor is provided in plurality, the plurality of first circuits are electrically connected, in one-to-one correspondence, to the plurality of light emitting elements, respectively, the plurality of first transistors are electrically connected, in one-to-one correspondence, to the plurality of first circuits, respectively, and the plurality of second transistors are electrically connected, in one-to-one correspondence, to the plurality of first circuits, respectively.

19. The display device of claim 14, wherein the driving transistor is an N-type thin film transistor.

20. A method of driving a display device comprising a pixel including a first circuit including a driving transistor including a first electrode, a second electrode, a gate electrode, and a back gate electrode, and a light emitting element including an anode, and a cathode connected to the first circuit,

initializing the cathode of the light emitting element; compensating by applying a voltage obtained by adding a threshold voltage of the driving transistor to a second compensation voltage to the gate electrode of the driving transistor by applying a first compensation voltage to the back gate electrode of the driving transistor and applying the second compensation voltage to the first electrode of the driving transistor; and allowing the light emitting element to emit light by allowing a current, from which an influence of the threshold voltage of the driving transistor is removed, to flow from the first electrode of the driving transistor to the second electrode thereof.

21. An electronic device, comprising:
a first circuit which is electrically connected to a data line, a plurality of scan lines, and a plurality of voltage lines, and includes a driving transistor including a first electrode, a second electrode, a gate electrode, and a back gate electrode;
a light emitting element including an anode, and a cathode connected to the first circuit; and
a second circuit including a first transistor connected between the back gate electrode of the driving transistor and a compensation voltage line, and a second transistor connected between the back gate electrode of the driving transistor and a first voltage line among the plurality of voltage lines.
